Edward P. Breneman,
INVENTOR
BY Victor J. Evans
ATTORNEY

P. Hickey

WITNESS:

UNITED STATES PATENT OFFICE

EDWARD P. BRENEMAN, OF ST. PAUL, MINNESOTA

ASH RECEIVER FOR AUTOMOBILES

Application filed August 4, 1927, Serial No. 210,592. Renewed June 19, 1929.

This invention relates to a receptacle for closed motor vehicles, the general object of the invention being to provide means whereby the receptacle can be suspended from or hung 5 on the window ledge of the interior of a vehicle and be readily removed at the convenience of the user so that ashes, matches, cigarette and cigar stubs, and the like, can be placed in the same by any occupant of the 10 vehicle.

Another object of the invention is to provide means for extinguishing a cigarette or cigar or scraping off ashes therefrom and for supporting a cigarette or cigar in the top of 15 the receptacle so that it can be easily picked up by the user.

This invention also consists in certain other features of construction and in the combination and arrangement of the several parts, to 20 be hereinafter fully described and illustrated in the accompanying drawing and specifically pointed out in the appended claims.

In describing my invention in detail, reference will be had to the accompanying drawing 25 wherein like characters denote like or corresponding parts throughout the several views, and in which:

Figure 1 is a view showing the receptacle hung on the window ledge (window sill) of 30 a vehicle.

Figure 2 is a plan view of the device.

Figure 3 is a section on line 3—3 of Figure 2.

Figure 4 is a view similar to Figure 3, but 35 showing a slight modification.

In these views, 1 indicates a box-like receptacle which has its rear side extended upwardly and bent twice at right angles to form a hook-like part 2 which is adapted to be placed 40 over the window ledge in the interior of an automobile to support the receptacle, as in Figure 1, so that ashes, matches and the like can be placed in the receptacle by the occupants of the automobile.

45 Inwardly extending ears 4 are attached to the inner side wall of the receptacle and have their inner ends slightly spaced apart. The ears are rounded, as shown in Figure 2, so that these edges can be used for extinguishing 50 a cigarette or cigar or scraping ashes or sparks

from cigarettes or cigars. These ears also form a rest for a cigarette or cigar to support the same until the smoker is ready to use the cigarette or cigar again.

Figure 4 shows the ears provided with depending jaw parts 5 to grip the cigarette or cigar and thus insure it not falling into the receptacle.

With this device, ashes, burnt matches, cigarette and cigar stubs and the like need not 60 be thrown upon the floor or from the windows, as they can be placed in the receptacle. The hanger of the receptacle is so constructed to support the receptacle by merely placing the same over the window ledge without the use 65 of screws or other fastenings, making it easy to move the same from one place to another so that it may be within reach of the user and can be easily removed and emptied when necessary.

70 It is thought from the foregoing description that the advantages and novel features of my invention will be readily apparent.

I desire it to be understood that I may make 75 changes in the construction and in the combination and arrangement of the several parts, provided that such changes fall within the scope of the appended claims.

What I claim is:

1. An ash receiver and cigarette and cigar 80 holder for automobiles comprising a receptacle having an extension at the top of one side thereof, said extension being bent into hook shape for providing means for attaching the receptacle to a part of the vehicle, a 85 pair of inwardly extending tongues connected with the interior wall of the receptacle adjacent the top thereof, said tongues being arranged opposite each other and of tapered shape, said tongues providing extinguishing 90 means for cigarettes and cigars and for scraping ashes therefrom and forming a support for a cigarette or cigar.

2. An ash receiver and cigarette and cigar 95 holder for automobiles comprising a receptacle having an extension at the top of one side thereof, said extension being bent into hook shape for providing means for attaching the receptacle to a part of the vehicle, a pair of inwardly extending tongues con- 100

neeted with the interior walls of the receptacle adjacent the top thereof, said tongues being arranged opposite each other and of tapered shape, said tongues providing extinguishing means for cigarettes and cigars and for scraping ashes therefrom and forming a support for a cigarette or cigar, each tongue having an extension at its inner end which is bent downwardly and curved to provide gripping means for a cigarette or cigar.

10 In testimony whereof I affix my signature.
EDWARD P. BRENEMAN.
